(57) **CLAIM**

The ornamental design for a breeze blocker, as shown and described.

DESCRIPTION

FIG. 1 is a front view of the breeze blocker, showing our new design;

FIG. 2 is a left elevation view thereof;

FIG. 3 is a right elevation view thereof;

FIG. 4 is a rear elevation view of thereof;

FIG. 5 is a bottom plan view thereof;

FIG. 6 is a top plan view thereof;

FIG. 7 is a side view of the breeze blocker in rolled configuration;

FIG. 8 is a front elevation view illustrating support poles as shown in FIGS. 1-7 for use with the breeze blocker;

FIG. 9 is a front elevation view of the breeze blocker in a rolled configuration;

FIG. 10 is a rear elevation view thereof;

FIG. 11 is a perspective view of the breeze blocker as shown in FIGS. 1-6;

FIG. 12 is a perspective view of the breeze blocker in a rolled configuration as shown in FIGS. 9 and 10; and,

FIG. 13 is a perspective view of the breeze blocker as shown in FIGS. 1-6.

The broken lines in FIG. 13 illustrating a person using the breeze blocker is for illustrative purposes only and forms no part of the design.
